(57) **CLAIM**

The ornamental design for a wax candle vessel, as shown and described.

DESCRIPTION

FIG. 1 is a perspective view of a wax candle vessel illustrating an embodiment of our new design;

FIG. 2 is a side elevation view thereof, all sides being identical;

FIG. 3 is a top plan view thereof;

FIG. 4 is a bottom plan view thereof;

FIG. 5 is a sectional view of the vessel taken along line 5-5 of FIG. 2;

FIG. 6 is a perspective view of a wax candle vessel illustrating another embodiment of our new design;

FIG. 7 is a side elevation view thereof, all sides being identical;

FIG. 8 is a top plan view thereof;

FIG. 9 is a bottom plan view thereof;

FIG. 10 is a sectional view of the vessel taken along line 10-10 of FIG. 7;

FIG. 11 is a perspective view of a wax candle vessel illustrating still another embodiment of our new design;

FIG. 12 is a side elevation view thereof, all sides being identical;

FIG. 13 is a top plan view thereof;

FIG. 14 is a bottom plan view thereof; and,

FIG. 15 is a sectional view of the vessel taken along line 15-15 of FIG. 12.

In the drawings, the broken lines depict environmental subject matter only that forms no part of the claimed design.

1 Claim, 15 Drawing Sheets
